United States Patent Office.

RICHMOND HATHAWAY, OF CHICOPEE, MASSACHUSETTS, ASSIGNOR TO
HIMSELF AND LEVI O. ALLEN, OF GARDINER, MAINE.

Letters Patent No. 78,523, dated June 2, 1868.

IMPROVED CLOTH AND CLOTHES-PIN.

The Schedule referred to in these Letters Patent and making part of the same.

TO ALL WHOM IT MAY CONCERN:

Be it known that I, RICHMOND HATHAWAY, of Chicopee, Hampden county, Commonwealth of Massachusetts, have invented certain new and useful Improvements in Cloth and Clothes-Holders; and I do hereby declare that the following is a full and exact description thereof, reference being had to the accompanying drawings, and to the letters of reference marked thereon.

In the drawings—

Figure 1 is a plan view and

Figure 2 a side view of my device, while

Figure 3 represents it as opened by the pressure of a finger and thumb of the operator,

Figure 4 showing its application as a clothes-pin.

This invention consists of a simple and conveniently-arranged device for holding clothes upon the line, as well as numerous other similar operations.

In construction, it is formed so that it can be operated by the thumb and fore-finger of the operator, so as to open the jaws, while the spring of the material forming the device causes the jaws always to close, unless held open by force.

In the drawings, it is shown that the device is formed of a single spring-wire, bent around so as to form a coil-spring, *a*, in the centre; jaws *b* and *c*, and levers *d* and *d*, for the purpose of operating the jaws. It is also shown that one of the jaws, *b*, consists of a sharp point, bent over at right angles to the shank, so that it enters, when shut, the ring *c* forming the other jaw; this ring being formed by the shank being bent around until the end meets the straight part. The levers *d* and *d*, formed by the bending of the wire out and back, consist of two wires to each lever, so that they are easily handled, while the spring *a*, formed by the coiling of the wire at the return bend of the same, after it has formed the levers, gives the greatest amount of elasticity to the device possible.

This device is very convenient for the use of seamstresses and tailors, for cutting out their patterns and basting them, they being very cheaply manufactured, and operating in the simplest manner to hold the cloth securely together, the arrangement of the jaws preventing the possibility of two or more pieces thus held together from slipping.

Now, having described my invention, what I claim as new, and desire to secure by Letters Patent, is—

An article of manufacture, the clothes-pin constructed as described, viz, with the central coil *a*, the levers *d* *d*, the central depressions to admit the line, and the pointed and ring-jaws, all as set forth.

RICHMOND HATHAWAY.
